UNITED STATES PATENT OFFICE.

LEON S. DEASON, OF PHENIX CITY, ALABAMA, AND RAYMOND A. BOWLES, OF COLUMBUS, GEORGIA, ASSIGNEES, BY DIRECT AND MESNE ASSIGNMENTS, OF ONE-THIRD TO SAID BOWLES, ONE-THIRD TO WILLIAM E. PAGE, AND ONE-THIRD TO WILLIAM A. BARR, JR., BOTH OF COLUMBUS, GEORGIA.

CARBURETOR.

Application filed June 13, 1923. Serial No. 645,143.

To all whom it may concern:

Be it known that we, LEON S. DEASON and RAYMOND A. BOWLES, citizens of the United States, residing at Phenix City, 5 in the county of Lee and State of Alabama, and Columbus, in the county of Muscogee and State of Georgia, respectively, have invented certain new and useful Improvements in Carburetors, of which the following is a specification.

This invention relates to carburetors and has special reference to a carburetor particularly designed and adapted for use with acetylene gas.

15 In the construction of carburetors such as are used in connection with gasoline and other like liquid hydro-carbons it is common to introduce the fuel in an upward direction through a jet nozzle located axially of a 20 Venturi tube. This practice is found inadmissible when acetylene is used as the fuel since the entire action of such a carburetor depends on suction whereas, when acetylene constitutes the fuel, the gas is supplied 25 under pressure and will continue to flow through the nozzle in the intervals between the suction strokes of the engine to which the carburetor is connected; the consequence being that there is an accumulation of gas at 30 improper times and an unevenness in the mixture produced so that, at times, explosions take place within the carburetor and, at other times, the engine misses fire.

It has been found that a carburetor constructed and arranged to produce a downward stream of acetylene gas and provided with proper means for ensuring a thorough mixing of the fuel and air will obviate all objections to the use of acetylene as a fuel 40 for internal combustion engines and it is the principal object of the present invention to provide a novel and improved carburetor embodying the principles just noted and obviating the difficulties found in using 45 a carburetor of the common type with acetylene as a fuel.

With the above and other objects in view, as will be hereinafter apparent, the inven-

tion consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of a carburetor constructed in accordance with this invention, the view showing the cam fingers in running position and the device connected to an elbow for attachment to the intake manifold of an internal combustion engine.

Figure 2 is a vertical median section through such a carburetor.

Figure 3 is a detail side view of a certain instrumentation used in the carburetor to ensure proper distribution of entering air.

Figure 4 is a section on the line 4—4 of Figure 2.

In the embodiment of the invention herein illustrated there is provided a shell or body having a relatively small upper end 10 and a relatively large lower end 11. The lower part of the end 11 is internally threaded to receive the central portion 12 of a tubular member which has its upper end of reduced size as shown at 13 so as to provide a gas chamber 14 within the end 11 of the shell. Between the portions 12 and 13 this tubular member is of frusto-conical form, as at 15, 70 to provide a seat for a valve 16 which not only controls communication between the air inlet chamber 17 within the upper part 10 of the shell and the mixing chamber 18 within the lower part of the tubular member 75 but also controls the passage of gas from the gas chamber 14 to said mixing chamber through the ports 19 formed in the frusto-conical portion 15 of the tubular member. 80

The upper end of the shell portion 10 is 90 internally threaded to receive a plug or cap 20 having a depending stem 21 carrying at its lower end an air distributor plate 22. This plate 22 fits closely within the upper end 13 of the tubular member and is provided with peripheral notches 23 so that air 95

entering the chamber 17 through the lateral ports 24 and flowing downwardly into the mixing chamber 18 is distributed in a series of streams close along the wall of the air chamber at its lower part, these streams flowing in between the streams of gas entering through the ports 19 so that the gas first finds its way to the center of the down flowing stream and then, owing to the frusto-conical shape of the valve, is forced outwardly in a thin frusto-conical sheet together with the air and thus becomes most intimately mixed therewith.

The plug and its stem have a central opening for the passage of a valve stem 25 connected to the valve 16 and having at its upper end an extension 26 which passes through the top of a spring cage or cap screwed onto the upper end of the plug 20. This spring cage is shown at 27 and it will be seen that there is housed therein a spring 28 which bears at its upper end against a collar 29 formed on the extension 26 so that the valve is constantly urged to closed position. Above the valve spring cage 27 a second spring 30 surrounds the extension 26 and bears at its upper end against a sliding collar 31. Pivoted to the upper end of the extension 26 is a cam finger 32 which, when raised, compresses the second spring 30 to such an extent that the valve 16 is practically locked in seated position, the finger being turned down as shown in Figure 2 when in running position. Acetylene is supplied to the gas chamber from a suitable generator or storage tank (not shown) through a supply tube 33 and the inflowing air is controlled by a ported tubular air valve 34 provided with an operating handle 35. Moreover, the lower end of the tubular member is threaded so that an elbow 36 may be screwed thereon to enable the device to be attached to the intake manifold of an internal combustion engine in the usual manner.

In operation, as above noted, the finger 32 is turned down. With each suction stroke of the engine the valve 16 will be opened and air and fuel will rush in to the mixing chamber in the manner described and from thence will pass through the elbow 36 to the intake manifold of the engine. The carburetor thus provides for the downward flow of both air and fuel and the thorough mixing of the two as they pass down.

There has thus been provided a simple and efficient device of the kind described and for the purpose specified.

It is obvious that changes may be made in the form and construction of the device without departing from the material principles involved. It is not therefore desired to confine the invention to the exact form herein shown and described but it is desired to include all such as properly come within the scope claimed.

Having thus described the invention, what is claimed as new, is:

1. A carburetor of the class described including an outer shell, an inner tubular member arranged within the outer shell and spaced at one part therefrom to provide a fuel chamber having port communication with the inner tubular member, the upper end of the shell and lower end of the tubular member constituting respectively an air chamber and a mixing chamber, and a single valve controlling the communication between the air and mixing chambers and the port communication between the fuel chamber and the inner tubular member. 80

2. A carburetor of the class described including an outer shell, an inner tubular member arranged within the outer shell and spaced at one part therefrom to provide a fuel chamber having port communication with the inner tubular member, the upper end of the shell and lower end of the tubular member constituting respectively an air chamber and a mixing chamber, a single valve controlling the communication between the air and mixing chambers and the port communication between the fuel chamber and the inner tubular member, and means at the lower end of the air chamber to distribute the air flowing downwardly therefrom in a plurality of streams. 90

3. A carburetor of the class described including an outer shell, an inner tubular member arranged within the outer shell and spaced at its upper part therefrom to provide a fuel chamber, said tubular member being provided with spaced ports affording communication from the fuel chamber to the interior of the tubular member, the upper end of the shell and the lower end of the tubular member constituting respectively an air chamber and a mixing chamber, a single valve controlling the communication between the air and mixing chambers and from the fuel chamber through said ports, and an air distributing plate in the lower part of said air chamber arranged to direct streams of air downwardly between the streams of gas flowing through said ports. 100

4. A carburetor of the class described including an outer shell, an inner tubular member arranged within the outer shell and spaced at one part therefrom to provide a fuel chamber having port communication with the inner tubular member, the upper end of the shell and lower end of the tubular member constituting respectively an air chamber and a mixing chamber, a single valve controlling the communication between the air and mixing chambers and the port communication between the fuel chamber and the inner tubular member, and spring means constantly urging said valve to closed position. 110

5. A carburetor of the class described including an outer shell, an inner tubular member arranged within the outer shell and spaced at one part therefrom to provide a fuel chamber having port communication with the inner tubular member, the upper end of the shell and lower end of the tubular member constituting respectively an air chamber and a mixing chamber, a single valve controlling the communication between the air and mixing chambers and the port communication between the fuel chamber and the inner tubular member, means at the lower end of the air chamber to distribute the air flowing downwardly therefrom in a plurality of streams, and spring means constantly urging said valve to closed position. 70

6. A carburetor of the class described including an outer shell, an inner tubular member arranged within the outer shell and spaced at its upper part therefrom to provide a fuel chamber, said tubular member being provided with spaced ports affording communication from the fuel chamber to the interior of the tubular member, the upper end of the shell and the lower end of the tubular member constituting respectively an air chamber and a mixing chamber, a single valve controlling the communication between the air and mixing chambers and from the fuel chambers through said ports, an air distributing plate in the lower part of said air chamber arranged to direct streams of air downwardly between the streams of gas flowing through said ports, spring means constantly urging said valve to closed position, and manually controllable means to increase the tension of said spring means and thereby prevent operation of said valve. 95
7. A carburetor of the class described including an outer shell, an inner tubular member arranged within the outer shell and spaced at one part therefrom to provide a fuel chamber having port communication with the inner tubular member, the upper end of the shell and lower end of the tubular member constituting respectively an air chamber and a mixing chamber, a single valve controlling the communication between the air and mixing chambers and the port communication between the fuel chamber and the inner tubular member, spring means constantly urging said valve to closed position, and manually controllable means to increase the tension of said spring means and thereby prevent operation of said valve. 115
8. A carburetor of the class described including an outer shell, an inner tubular member arranged within the outer shell and spaced at one part therefrom to provide a fuel chamber having port communication with the inner tubular member, the upper end of the shell and lower end of the tubular member constituting respectively an air chamber and a mixing chamber, a single valve controlling the communication between the air and mixing chambers and the port communication between the fuel chamber and the inner tubular member, means at the lower end of the air chamber to distribute the air flowing downwardly therefrom in a plurality of streams, and spring means constantly urging said valve to closed position, and manually controllable means to increase the tension of said spring means and thereby prevent operation of said valve. 130

of said extension, a compression spring on the top of said spring casing and bearing at its upper end against the sliding collar, and a cam finger pivoted to the upper end of the extension and bearing on said sliding collar, said cam finger being arranged to force the collar downward and thereby com-

press the second spring upon being turned on its pivot to a predetermined position. In testimony whereof, we hereunto affix ¹⁰ our signatures.

LEON S. DEASON.

RAYMOND A. BOWLES.
